(57) **CLAIM**

The ornamental design for a valve with handle, as shown and described.

DESCRIPTION

FIG. 1 is an isometric perspective front view of a valve with handle according to the present invention;

FIG. 2 is a front view of the valve with handle of FIG. 1; FIG. 3 is a right side view of the valve with handle of FIG. 1;

FIG. 4 is a left side view of the valve with handle of FIG. 1;

FIG. 5 is a rear view of the valve with handle of FIG. 1; FIG. 6 is a top view of the valve with handle of FIG. 1; FIG. 7 is a bottom view of the valve with handle of FIG. 1; FIG. 8 is an isometric perspective front view of a valve with handle according to a second embodiment of the present invention;

FIG. 9 is a front view of the valve with handle of FIG. 8; FIG. 10 is a right side view of the valve with handle of FIG. 8;

FIG. 11 is a left side view of the valve with handle of FIG. 8;

FIG. 12 is a rear view of the valve with handle of FIG. 8; FIG. 13 is a top view of the valve with handle of FIG. 8; and, FIG. 14 is a bottom view of the valve with handle of FIG. 8.

The broken lines shown in the figures are for the purpose of illustrating portions of the valve with handle and form no part of the claimed design.

1 Claim, 14 Drawing Sheets
